R. MOHN

ENVELOPE CLOSING MACHINE

Filed March 3, 1926

Inventor:

Rudolf Nohn.

Patented Jan. 4, 1927.

UNITED STATES PATENT OFFICE.

RUDOLF MOHN, OF SULGEN, SWITZERLAND, ASSIGNOR TO WILLY MÜLLER, OF THAL CANTON ST. GALLEN, SWITZERLAND.

ENVELOPE-CLOSING MACHINE.

Application filed March 3, 1926, Serial No. 92,081, and in Switzerland July 22, 1925.

This invention relates to a machine for moistening the sealing flaps of envelopes and sticking them to the bodies of the envelopes, and the invention consists in the provision of 5 a box having an opened side through which a moistening pad is rocked for application to a sealing flap projecting downwards from an envelope placed on the top of the box, a pair of press rollers being arranged so as to 10 receive the moistened envelope as the latter is fed forward by a feeding device, the latter as well as the moistening pad and the rollers being operated by means of a shaft and a 15 crank handle.

Fig. 1 of the accompanying drawings represents a front view of the machine,

Fig. 2, a plan view, and

Fig. 3, an end view of the same.

A box 2 has a bottom to which it is connected by angle irons 3. The rear side of the box is open so that a moistening pad 40 can be applied, from inside the box, to an upright plate 48 arranged at the open side of the box and spaced from the latter. The 25 upper edge of the plate 48 is bent over at right angles and held in alignment with the top plate 4 of the box. The moistening pad 40 consists of an asbestos strip which is clamped between metal strips 38 and 39 and 30 bent together with the latter so as to form two limbs which coincide with the gummed edge of the sealing flap of an envelope to be closed. The pad is connected by an arm 37 to a rock shaft 26 which is held in brackets 35 and 28 on the box. There is a tray 41 in 35 the box into which the pad dips for the reception of moistening liquid after each application to the plate 48. For rocking the shaft 26 and the pad, a lever 32 is pivoted at 40 36 to the right end wall of the box 2 and connected by a link 31 to an arm 30 secured to the rock shaft. The operating shaft 9 of the machine is rotated by means of a crank handle 34 and carries a cam 10 which operates 45 the lever 32 by engagement with an anti-friction roller 35 held in a fork 33 on the lever. A spring 29 on the shaft tends to apply the pad 40 to the plate 48 and holds 50 the roller 35 against the cam.

A pair of press rollers 42 and 43 are mounted in brackets 44 at the open side of the box. The lower roller 43 is larger than the upper one and has its top surface about on a level with the top plate 4. The upper 55 roller 42 is guided in the upper, forked ends

of the bracket 44 and is held against the roller 43 by springs 45. A pair of intermeshing bevel gears 46 one of which is mounted on the shaft of the roller 43 and the other on the end of the operating shaft 60 9, transmits motion from the latter to the press rollers.

A feeding device is provided in the form of two lever arms 20 which are carried by a rock shaft 21 inside the box and which are 65 brought up through elongated slots 18 and 19 in the top wall 4 of the box. The shaft 26 is held in bearings 22 and 23, and one end projects to the right end wall of the box where it is fitted with a collar 24 carrying a 70 radial arm 25. A spring 49 tends to turn the shaft 21 and holds the arm 25 against a cam 11 mounted on the operating shaft 9. A crest on the cam 11, acting on the arm 25, moves the arm 20 towards the press rollers. 75

The envelopes are placed on the top plate 4, the opened sealing flap being inserted through the slit 47 formed between the plate 48 and the edge of the plate 4, whereupon the operating shaft is turned by means of a 80 handle 34. This causes the moistening pad to be raised from the tray 41 and to be applied to the sealing flap against the plate 48 so as to moisten the gummed edge of the same. As the pad recedes, the arms 20 are 85 moved forward so as to push the moistened envelope in between the press rollers 42 and 43, the sealing flap, which is closed as it passes over the edge of the plate 48, being 90 stuck to the body of the envelope as the latter passes between the rollers.

The top plate 4 has at one end an extension 8 which covers the operating shaft and which is curved concentrically with the latter. An envelope guide 16 is arranged across 95 the top plate. This guide is adjustable and is secured to the plate by screws 17 which are guided in slots 14 and 15 in the plate. Another extension 5, on which the envelopes may be stacked, is hinged to the opposite end 100 of the plate 4 so that it can be folded against the end wall of the box. Foldable brackets 7 support the extension 5 in a horizontal position for use.

A counter 13 which records the operations, 105 is visible in a slot in the plate extension 8, as shown in Fig. 2. This counter is operated by the shaft 9 through the medium of a gearing 12.

I claim:

1. A letter closing machine comprising a box having an open side, a rock shaft held by said box at the open side thereof, a moistening pad connected to said shaft so that it ⁵ can be applied from the inside of the box to the sealing flap of an envelope placed on the top of the box with said flap extended downwards at the open side of the box, a pair of press rollers arranged at the open ¹⁰ side of the box, means for feeding the moistened envelope along the top of the box to the press rollers, an operating shaft, and means for transmitting motion from said

operating shaft to the rock shaft, to the press rollers and to the feeding means. ¹⁵

2. In a machine as claimed in claim 1, feeding means comprising a pair of lever arms projecting through slots in the top of the box, and a rock shaft for operating said arms. ²⁰

3. A machine as claimed in claim 1 in which the press rollers are of different size, the upper roller being the smaller, and means for holding the upper roller resiliently against the lower one. ²⁵

RUDOLF MOHN.
